Des. 240,189
Patented June 8, 1976

240,189

PORTABLE DESOLDERING TOOL OR THE LIKE

William S. Fortune, 14250 Dearborn St.,
Panorama City, Calif. 91402

Filed Oct. 15, 1974, Ser. No. 514,952

Term of patent 14 years

Int. Cl. D8—05

U.S. Cl. D8—51

Fig. 1

Fig. 2

Fig. 3

Fig. 4

Fig. 5

FIG. 1 is a left side elevational view of a portable desoldering tool or the like embodying my new design, the right side elevational view thereof being a mirror image of the illustrated left side;

FIG. 2 is a plan view thereof;

FIG. 3 is a bottom view thereof;

FIG. 4 is a front, elevational view thereof; and

FIG. 5 is a rear, elevational view thereof.

I claim:

The ornamental design for a portable desoldering tool or the like, substantially as shown and described.
